UNITED STATES PATENT OFFICE.

JOHN S. HOBSON, OF EDGEWOOD PARK, PENNSYLVANIA.

DETECTOR-BAR.

No. 893,169.

Specification of Letters Patent.

Patented July 14, 1908.

Application filed October 22, 1907. Serial No. 398,677.

To all whom it may concern:

Be it known that I, JOHN S. HOBSON, a citizen of the United States, residing at Edgewood Park, in the county of Allegheny and State of Pennsylvania, have invented certain new and useful Improvements in Detector-Bars, of which the following is a specification.

My invention relates to detector bars, which, as is well known in the art, are used in connection with railway switches.

My invention particularly relates to detector bars located on the inside of a rail as distinguished from the outside of the rail which has been the usual arrangement heretofore.

An advantage of using, what may be termed an inside detector bar, resides in the fact that with an inside detector bar all danger of the bar being thrown when a car or train is over it is entirely eliminated, since an inside detector bar would strike directly against the flange of a car wheel, whereas an outside bar has only that portion of the wheel projecting beyond the rail head to engage. Thus a greater factor of safety is obtained by the use of an inside detector bar.

I will describe a detector bar embodying my invention and then point out the novel features in claims.

In the accompanying drawings, Figure 1 is a side elevation of an inside detector bar embodying my invention. Fig. 2 is a vertical cross sectional view taken on the line 2—2 of Fig. 1. Fig. 3 is a vertical cross-sectional view taken on the line 3—3 of Fig. 1. Fig. 4 is a detail view, in side elevation of a modified form of motion plate in connection with a detector bar and embodying my invention. Fig. 5 is a vertical sectional view taken on the line 5—5 of Fig. 4.

Similar letters of reference designate corresponding parts in all of the figures.

A designates a railroad rail, and B a wheel of a car traveling along the rail.

C designates a detector bar which as shown is located alongside the rail A in such position as to engage the flange of the wheel B

when it is raised. This arrangement necessitates the detector bar being arranged on the "inside" of the rail. As shown the detector bar C is made from a channel iron or from two or more pieces c of angle iron which are bolted or riveted together at suitable points in such manner as to form a channel bar or to be U-shaped in cross section. The detector bar is supported in position alongside the rail by means of one or more clips D which are suitably secured by bolts d to the rail. Means are provided between the bar and clip for causing the bar to rise and fall along the rail, as well as means for preventing lateral and vertical displacement of the bar relatively to the rail. The clips D of Figs. 1 and 2, as shown, comprise two upright portions or walls d', d'', and a cam surface d³ having oppositely inclined sides.

Journalized within the side walls of the detector bar is one or more rollers c (according to the number of clips D employed) which are designed to travel up and down the oppositely inclined sides of the cam surface d³ when the detector bar is moved longitudinally by any desired means. The walls d', d'' of the clips prevent any lateral movement of the detector bar, and means are also provided for preventing the detector bar being lifted out of the clips. As shown in Figs. 1 and 3, these means take the form of bolts or pins E provided at intervals in the detector bar. The ends of the bolts or pins E project beyond the detector bar in such position as to engage the head of the rail when the detector bar is lifted vertically. If desired the cam surface may be carried by the detector bar and the roller by the clip.

Referring now to Figs. 4 and 5, the same form of detector bar is used, while a different form of clip is employed. In addition to the cam surface d³, an angular groove d⁶ (preferably conforming to the cam surface d³) is employed in which an end or head of the journal pin of the rollers c projects. The groove d⁶ and head of the pin are for the same function as the pins or bolts E and also for the purpose of forcing the detector bar downward after

it has passed over the apex of the cam surface d^3 .

Having thus described my invention, what I claim as new is:—

5 The combination with a detector bar U-shaped in cross-section, of a roller journaled in the walls of the detector bar, a clip for supporting said bar in position, said clip having side walls and a cam surface over which the

roller travels, and means for limiting the 10 upward movement of the bar.

In testimony whereof I have signed my name to this specification in the presence of two subscribed witnesses.

JOHN S. HOBSON.
